Primary Examiner — S. Bryan Reinholdt, Jr.

Assistant Examiner — Kaitlan Walker

(57) **CLAIM**

The ornamental design for a firearm grip, as shown and described.

DESCRIPTION

FIG. 1 is a front, left perspective view of a firearm grip. FIG. 2 is a right side view of the firearm grip of FIG. 1. FIG. 3 is a left side view of the firearm grip of FIG. 1. FIG. 4 is a front view of the firearm grip of FIG. 1. FIG. 5 is a rear view of the firearm grip of FIG. 1. FIG. 6 is a top view of the firearm grip of FIG. 1. FIG. 7 is a bottom view of the firearm grip of FIG. 1; and, FIG. 8 is a bottom, right perspective view of the firearm grip of FIG. 1. The broken lines and the unshaded areas adjacent to them depict portions of a firearm grip that form no part of the claimed design.

1 Claim, 8 Drawing Sheets
